SPEED RESPONSIVE GOVERNOR HAVING
ITS OUTPUT MEMBER COMPOSED OF A
DRY LUBRICATING SUBSTANCE

Werner E. Armstrong, Milwaukee, Wis.

Application October 11, 1952, Serial No. 314,269

3 Claims. (Cl. 264—15)

1

This invention relates to governors of the mechanical-centrifugal type and to an improvement in the same suitable for use in governing the speed of small internal combustion engines and other machines having a throttle, and it resides more specifically in a governor in which a spring loaded governor follower is carried in a detachable mounting-cover enclosing a centrifugal assembly the mounting-cover being readily removable without disturbing the adjustment of the follower or the centrifugal assembly, and in which the centrifugal force prevailing in the centrifugal assembly is translated into axial thrust which is communicated to the follower by a dry-lubricated transmitting member which may be readily inspected, removed and replaced when the mounting-cover is detached.

In some compact governors capable of exerting sufficient force to reliably actuate the throttle of a small internal combustion engine it has heretofore been difficult to provide means which would effectively translate centrifugal force exerted by the governor into sufficient thrust to be effective to regulate the throttle opening without resort to expensive constructions. Furthermore, such governors heretofore available have been constructed in such fashion that ready inspection, adjustment and repair of the same has not been possible since the housings provided therefore may only be opened for repair purposes with an accompanying upsetting of the arrangement and adjustment of parts.

It is one object of this invention to provide an improved governor of the class heretofore referred to wherein centrifugal force is translated into axial thrust and communicated along the axis of the governor shaft by a member composed of a dry-lubricating solid, which by reason of its inherent lubricating properties moves with little friction with reference to the axial guides which restrain it, with respect to the centrifugal members which act upon it and with respect to the governor follower in contact therewith.

Another object of this invention is to provide a governor wherein the wear occurring therein is slight and is confined chiefly to a single unitary motion transmitting member composed of a dry-lubricating solid which can be rendered accessible without disturbance of governor adjustment for ready removal and replacement.

Another object of this invention is to provide a governor of the class described wherein axial thrust communicated from the rotating centrifugal assembly is imparted to a nonrotating follower having a plain, smooth face engaged by the

10 contacting rotating end of a motion transmitting member the latter being composed of a dry-lubricating solid.

The foregoing and other objects and advantages of this invention will appear from the description following which is set forth with the aid of the accompanying drawing which forms a part hereof, and in which there is described and shown by way of illustration and not of limitation one form in which the governor of this invention may be embodied.

In the drawing:

Fig. 1 is a side view in elevation and in section of one form of the governor of this invention;

Fig. 2 is a fragmentary detailed side view in section of the centrifugal assembly and follower of the governor shown in Fig. 1 with the parts occupying a position corresponding with the condition prevailing under rapid rotation;

Fig. 3 is a side view in elevation of the exterior of the governor shown in Fig. 1; and

Fig. 4 is a detailed fragmentary view in perspective of the centrifugal assembly and follower of the governor shown in Fig. 1.

The governor of this invention, in the form appearing in the drawing, may be constructed to be mounted upon a portion of a machine to be governed, indicated by the numeral 1, which portion furnishes support for bearings 2, 3 and 4 acting to mount a governor shaft 5 for rotation. A gear or other driving means 6 mounted upon the shaft 5 may be associated in driven relation with a rotating part of the machine to be governed not shown. The upper portion of the governor shaft 5 is enlarged to provide a hub 7 which furnishes a seat for a U shaped pivot bracket 8 surrounding the same and held securely in place by the riveted edge of a shoulder projecting upwardly from the hub 7 as indicated at 9.

The shaft 5 extends upwardly from the hub 7 to form a tubular extension 10 which is intersected by a transverse opening providing a pair of access channels 11 and 12 at the sides thereof. Pivotaly carried on pivots 13 and 14, mounted in the pivot bracket 8, is a pair of centrifugal members 15 and 16, provided respectively with actuating toes 17 and 18 which enter the access channels 11 and 12 and terminate short of the axis of the shaft 5.

Mounted for free sliding axial movement within the bore of the tubular extension 10 is a motion transmitting member 19 composed of a solid material having dry-lubricating properties. For this purpose a carbonaceous body having a sub-

stantial graphitic content is preferred. Such a body may be prepared by calcification of carbonaceous and graphitic material in the presence of a binder such as pitch or the same may be formed by binding such carbonaceous materials with binding substances cured at lower temperatures. Other self-lubricating dry-solids may be prepared by saturating porous metallic material with hydrocarbon lubricants or by applying to metallic bodies coatings of dry-lubricating materials such as molybdenum sulphide and the like.

Surrounding the bearing 4 and held securely in place by a fastening 20 is a housing plate 21 having an upwardly facing circular groove near the outer rim thereof. Seated within the circular groove above mentioned in close fitting engagement therewith is the lower notched rim of a mounting-cover 22 which is indented as at 23 to provide a pivotal mounting for a follower shaft 24 upon which a follower 25 is carried as shown. The lower face of the follower 25 is plane and smooth and rests in contact with the rounded upper end of the motion transmitting member 19. Shaft 24 extends to the exterior of mounting-cover 22 where it is secured to a governor lever 26 as appears more clearly in Fig. 3.

The lower end of governor lever 26 is drilled to receive the offset end of a throttle rod 27 which may cooperatively engage the throttle of the machine to be governed. A governor loading spring 28 is attached through a similar drilled opening disposed close to the follower shaft 24, the opposite end of the same being secured to a speed controlling arm 29 pivotally carried at 30 and provided with a notched adjusting quadrant 31 which engages an arresting spring 32 secured to the housing plate 21 as shown.

Upon rotation of shaft 5 the centrifugal members 15-16 are urged outwardly by centrifugal force toward the position shown in Fig. 2 and in so doing the toes 17-18 bear against the motion transmitting member 19 urging the same upwardly against the follower 25. Motion is thus communicated to the governor lever 26 which in turn acts upon the throttle through the rod 27 so as to diminish fuel supplied to the machine being governed.

In the course of such motion friction between the toes 17-18 and member 19 is minimized by the inherent lubricating properties of the member 19. Frictional resistance to axial movement of the member 19 as it slides in the bore of the tubular extension 10 is likewise similarly restricted. At the same time, the upper contacting end of the member 19 turns freely in contact with the follower 25 with little friction and little wear by reason of the inherent lubricating properties of the member 19. As a result the action of the governor remains sensitive in proportion to the power available.

The rate of wear of the upper end of the member 19 under the conditions of operation described is moderate not only due to the notably long wearing properties of dry-lubricating materials but also because of the rounded configuration of the upper end of the member 19 which engages the smooth surface of the follower 25 with substantially a point contact which is aligned with the axis of rotation of member 19. Motion at this point contact is therefore at a minimum. The stress imposed by the follower being moderate the point contact is of ample strength to sustain the load and both friction and wear are held at a minimum. In cases of extreme service where governing action has be-

come impaired due to wear of the member 19, the spring clips 33-34 may be quickly removed to release the mounting-cover 22 after first disconnecting spring 28 and throttle rod 27. The entire centrifugal assembly may thus be exposed and the worn member 19 may be quickly removed and replaced by a similar member in proper condition for resumption of normal functioning of the governor. If desired the space enclosed by the mounting-cover 22 may also serve to house other auxiliaries of the apparatus to be governed which may require easy and rapid exposure to inspection since removal and replacement of mounting-cover 22 can be effected without derangement of the governor adjustment.

I claim:

1. In a governor for a rotating machine having a shiftable power admission throttle the combination comprising a rotatably mounted governor shaft having a free end and a driven end including means for connecting said shaft to a machine to be governed to be rotatably driven thereby, axial guiding means concentric with the axis of rotation of said shaft disposed at the free end of said shaft, an axially movable motion transmitting member composed of a dry-lubricating solid slidably mounted for axial movement in said axial guiding means and having a thrust communicating end extending beyond the free end of said shaft and an inwardly disposed thrust receiving end, centrifugal means carried on and rotatably driven by said shaft including force translating means cooperatively engaging the dry lubricating substance of the thrust receiving end of said motion transmitting member to exert an outward axial thrust thereon in response to centrifugal force exerted by said centrifugal means, a spring loaded movable follower member having a smooth plane follower face transversely disposed with respect to said axially movable motion transmitting member contacting the dry lubricating substance thereof and opposing axial motion of the thrust communicating end thereof, and throttle linkage means cooperatively engaging said follower member for cooperatively connecting the same to the throttle of said machine to be governed.

2. In a governor for a rotating machine having a shiftable power admission throttle the combination comprising a rotatably mounted governor shaft having a free end and a driven end including means for connecting said shaft to a machine to be governed to be rotatably driven thereby, an axial guide channel concentric with the axis of rotation of said shaft extending inwardly from the free end of said shaft, an axially movable motion transmitting member composed of a dry-lubricating carbon containing solid slidably mounted for axial movement in said axial guide channel and having a rounded thrust communicating end extending beyond the free end of said shaft and an inwardly disposed thrust receiving end, centrifugal means carried on and rotatably driven by said shaft including force translating means cooperatively engaging the dry lubricating substance of the thrust receiving end of said motion transmitting member to exert an outward axial thrust thereon in response to centrifugal force exerted by said centrifugal means, a spring loaded movable follower member having a smooth plane follower face transversely disposed with respect to said axially movable motion transmitting member contacting the dry lubricating substance thereof and opposing axial motion of the thrust communicating end thereof.

cating end thereof, and throttle linkage means cooperatively engaging said follower member for cooperatively connecting the same to the throttle of said machine to be governed.

3. In a governor for a rotating machine having a shiftable power admission throttle the combination comprising a rotatably mounted governor shaft having a free end and a driven end including means for connecting said shaft to a machine to be governed to be rotatably driven thereby, axial guiding means concentric with the axis of rotation of said shaft disposed at the free end of said shaft, an axially movable motion transmitting member slidably mounted for axial movement on said axial guiding means and having a thrust communicating end composed of dry lubricating substance extending beyond the free end of said shaft and an inwardly disposed thrust receiving end, centrifugal means carried on and rotatably driven by said shaft including force translating means cooperatively engaging the thrust receiving end of said motion transmitting member to exert an axial thrust thereon in response to centrifugal force exerted by said centrifugal means, a spring loaded pivoted follower 25

member having a smooth plane follower face, a housing for said governer comprising a fixed base portion surrounding said shaft, and a removable housing cover extending over the end of said shaft, said movable follower member being pivotally mounted on said cover to present the smooth flat face thereof in transverse contacting relation to the thrust communicating end of said thrust transmitting member when said housing cover is in place, and throttle linkage means cooperatively engaging said follower member for cooperatively connecting the same to the throttle of said machine to be governed.
